UNITED STATES PATENT OFFICE.

HENRY W. LYON, OF BRIDGEPORT, CONNECTICUT.

METHOD OF MAKING BUTTON-HOLE STRIPS.

SPECIFICATION forming part of Letters Patent No. 399,061, dated March 5, 1889.

Application filed December 3, 1888. Serial No. 292,446. (No model.)

To all whom it may concern:

Be it known that I, HENRY W. LYON, a citizen of the United States, residing at Bridgeport, in the county of Fairfield and State of Connecticut, have invented certain new and useful Improvements in the Method of Making Button-Holes; and I do hereby declare the following to be a full, clear, and exact description of the invention, such as will enable others skilled in the art to which it appertains to make and use the same.

My invention relates to the method of making button-hole strips, and has for its object to simplify the manufacture of button-holes, and also to greatly strengthen and re-enforce the button-hole strip itself; and with these ends in view my invention consists in the various steps followed in the manufacture of said strips, such as will be hereinafter fully set forth, and then specifically designated by the claims.

In the accompanying drawings, Figure 1 is a plan of the blank from which my button-hole strip is formed; Fig. 2, a plan showing said blank partially folded to constitute the strip; Fig. 3, a bottom view of the completed strip; Fig. 4, a central longitudinal section of said strip, the flaps of one button-hole being shown in position preparatory to folding; Fig. 5, a top view of the completed strip preparatory to binding; and Fig. 6, a similar view showing the side edges of the strip bound with tape, one end of the strip being turned up and sectioned.

Similar letters denote like parts in the several figures.

In the blank shown at Fig. 1 the long cuts 1 and short cuts 2 form T-heads 3, which when folded and manipulated, as presently set forth, constitute the flaps of the button-holes throughout the strip. These T-heads are formed at the sides of the strip 4, each head being folded upon itself, so as to form a two-ply flap, as is clearly shown in Fig. 2. 5 are the button-hole slits, which are cut within the central section of the strip in alignment with the various cross series of short cuts 2. After the flaps have been formed by folding the T-heads 3 upon themselves the sides of the strip are folded inward upon the central section of said strip, and the said T-headed flaps are passed through the slits 5. The manner of passing the flaps through

the slits is as follows: After folding the sides of the strip inward it will be seen that the 55 necks of the lower flaps are immediately above the slits, while the necks of the upper flaps are coincident with the necks of the lower flaps, and that the upper and lower flaps extend in opposite directions. It will be clearly 60 seen, therefore, that the formation of the button-hole is readily effected by inserting the two flaps in succession through the slits, then folding them in opposite directions against the strip, and finally stitching said flaps to 65 the strip, all of which is fully shown in Figs. 2, 3, 4, and 5.

In order that the button-holes may be firmly barred at the ends, I bind the latter on both sides with strips 6 of tape; but this barring 70 forms no part of my present invention, since it is a well-known way of securing the ends of a series of button-holes in a strip.

Having thus described my invention, what I claim as new, and desire to secure by Letters 75 Patent, is—

1. The method of making button-holes in a strip, the same consisting in cutting button-hole slits at suitable distances throughout the central section of the strip, forming T-headed 80 flaps at the sides of the strip, folding said flaps upon themselves, folding the sides of the strip inward, inserting said flaps in pairs through the slits, and folding the flaps backward in opposite directions against the strip, substantially 85 as set forth.

2. The method of making button-holes, which consists in forming a single blank having button-hole slits at proper intervals within the central section of said blank and T-headed 90 flaps within the opposite sides of said blank, doubling said flaps upon themselves and folding the sides of the blank inward, inserting the flaps through said slits and folding said flaps backward in opposite directions against 95 the blank, stitching the flaps to the blank, and finally barring the opposite ends of the button-holes, substantially as shown and set forth.

In testimony whereof I affix my signature in 100 presence of two witnesses.

HENRY W. LYON.

Witnesses:

S. S. WILLIAMSON,
A. T. HOLT.
